UNITED STATES PATENT OFFICE.

ELISHA CRAFT, OF WELLSBURG, WEST VIRGINIA.

ADJUSTABLE GOVERNOR FOR ENGINES.

1,136,940.

Specification of Letters Patent. Patented Apr. 27, 1915.

Application filed June 27, 1914. Serial No. 847,785.

To all whom it may concern:

Be it known that I, ELISHA CRAFT, citizen of the United States, residing at Wellsburg, in the county of Brooke and State of West Virginia, have invented certain new and useful Improvements in Adjustable Governors for Engines, of which the following is a specification.

My invention relates to governors and particularly to governors adapted to be used in connection with traction engines or saw-mill engines though not limited to this use.

Generally speaking the objects of my invention are first, to provide very simple means whereby the speed of the engine may be readily changed without changing or shifting the belt which connects the governor to the engine; second, to provide means for automatically closing the regulating valve if the belt breaks; and third, to provide means whereby the governor may be easily disconnected entirely from the driving shaft without the necessity of removing the belt from the driving shaft.

These objects and others will be more fully stated in the following specification.

My invention is illustrated in the accompanying drawings wherein: Figure 1 is a side elevation of the governor constructed in accordance with my invention, some of the parts being in section. Fig. 2 is a fragmentary elevation of the governor working from the opposite side to the view point in Fig. 1 and showing the gears disconnected. Fig. 3 is a fragmentary elevation partly in section to show the coupling between the upper and lower sections of the valve shaft and the latch whereby the lower section is held in engagement with the upper section under normal conditions. Fig. 4 is an enlarged sectional view on the same lines as the view taken in Fig. 1. Fig. 5 is a detail fragmentary elevation showing the coupling between the upper and lower sections of the valve shaft and the latch, the latch being shown in engagement with the coupling to prevent the dropping of the idler wheel. Fig. 6 is a fragmentary elevation of the collar whereby the upper bevel gear is raised or lowered.

Corresponding and like parts are referred to in the following description and indicated in all the views of the accompanying drawings by the same reference characters.

Referring to these drawings, 2 designates

the valve casing of the usual ordinary regulating valve or controlling valve of a steam engine or gas engine. Inasmuch as this valve and the casing are of ordinary construction, there is no necessity of giving any detailed description of these parts.

Mounted upon the casing 2 is the supporting frame 3 of the governor having projecting therefrom a bracket 4 which is tubular and through which the driving shaft 5 passes. This driving shaft is illustrated as carrying at its end a pulley designated generally 6 having the same construction as that illustrated in my Patent No. 1,019,305, granted March 5, 1912. Inasmuch as the particular form of this pulley has nothing to do with the present invention, a further description thereof is unnecessary.

Passing over the pulley 6 which is fast upon the shaft 5 is a band 7 whereby the shaft 5 is driven.

Carried upon the inner end of the shaft 5 is the bevel gear wheel 8. Passing into the valve casing 2 is the valve shaft. This shaft is made in two sections, the sections being designated, respectively, 9 and 10, as shown more clearly in Fig. 3. When the upper section 10 is lowered it has driving engagement with the section 9. The section 9, however, may be dropped with relation to the section 10 by means which will be hereafter described, but normally and when the parts are in working position the section 9 is held to the section 10 by means of a latch mechanism. To this end there is provided a coupling or sleeve 11 which surrounds the abutting ends of the sections 9 and 10 and which is pinned to the section 9 to move therewith. Passing through the coupling or sleeve is a latch member 12 which has sliding engagement through the coupling and one extremity of which is bent as at 13 and formed with an inwardly extending terminal tooth 14, this tooth being adapted to engage a notch 15 formed in the face of the shaft section 10, as shown clearly in Fig. 3. This detent tooth is held in engagement with the shaft section 10 by means of a spring 16 which surrounds the latch rod and which exerts pressure between the coupling 11 and a head 17 formed on the extremity of the latch rod. It will be therefore seen that under normal circumstances the section 10 will be locked to the section 9 by the detent 14, but that when this detent is forced in one direction as

toward the right in Fig. 3, the detent tooth will escape from its engagement of the upper section 10 of the shaft and as a consequence, the lower section of the shaft together with the coupling 11 may drop. The means for automatically causing the disengagement of the two sections of the shaft will be later stated.

The frame 3 extends upward around the 10 shaft as at 17 and inserted in this upward projecting boss or seat 17 is a tubular member 18 which at its lower end is screw-threaded in the seat or portion 17. The shaft section 10 extends upward entirely 15 through this tubular member. The tubular member is slotted as at 19 and passing through the shaft and through this slot is a transversely extending pin 20. It will be seen that the shaft may therefore rise or fall 20 within a predetermined distance with relation to the tubular member 18 but that the shaft will be prevented from any rotation.

Surrounding the lower portion of the 25 tubular member and rotatably supported upon the seat 17 is a head 21 having a downwardly extending portion 22 forming a sleeve loosely surrounding the tubular member or sleeve 18. A spring 23 surrounds the tube 18 and bears at its upper end against a 30 collar 24 which in turn bears against the pin 20. This collar as illustrated in Fig. 4 on its upper face is formed with an annular flange and the pin 20 is seated within this flange so that the flange retains the pin from 35 any lateral displacement. The lower end of the spring 23 bears against a cone 25 which in turn bears against a series of anti-friction balls 26 supported in a seat 27 formed upon the upper face of the head 21. The head 40 21 may therefore have free rotation around the tubular member 18 and is held downward upon the seat 17 by the spring 23.

Surrounding the downward extension 22 of the head 21 but mounted for rotation 45 therewith is a bevel gear wheel 28 which meshes with the bevel gear wheel 8 under normal circumstances. The gear wheel 28 has rotation with the head 21 but is free to move vertically with relation to the head 21 50 and upon the extension 22. To this end the gear wheel 28 is splined upon the extension 22. In order to provide for a movement of the head 21 and extension 22 relative to the gear wheel 28 without disconnecting the 55 gear wheels 28 and 8, I dispose between the underside of the head 21 and the upper face of the gear wheel 28 the coil spring 29. During a predetermined movement of the head 21 and its extension 22 this spring will 60 keep the gears in mesh but beyond the limits of this predetermined upward movement the gear wheel 28 will move with the head 21 and will be raised from its engagement with the gear wheel 8 so as to disconnect these 65 gear wheels, as will hereafter more clearly

appear. Each of the gear wheels 8 and 28 is provided with the annular shoulder 30 which when the gear wheels are in mesh engage with each other to prevent a too deep meshing of the gear wheels due to the 70 action of the spring 29.

The means for raising and lowering the head 21 and the gear wheel 28 will be later stated. Slidably supported upon the upper end of the tube 18 is a head 31 which is opposed to the head 21. This head has a downward extension 32 which loosely surrounds the upper end of the tube 18 and through this head the upper section 10 of the shaft passes. The head has an upward annular extension 33 which is exteriorly screw-threaded and engaging this extension is an annular cap 34 formed with a seat 35 for an anti-friction ball 36. Carried upon the upper end of the shaft 10 is a collar 37 85 which is concaved upon its upper face to provide a seat for the ball 36. It will be thus seen that the cap 34 may rotate with the head 31. The cap 34 is adjustable upon the head 31 and with relation to the rod 10 and when the cap is screwed downward, it will be obvious, that the rod 10 will be forced downward and that this will close the regulating valve to a greater extent than when the cap is adjusted upward. The cap is 90 held in its adjusted position by means of a set screw 38.

The governor balls 39 are mounted upon flat springs 40, the upper and lower ends of 100 which are connected in any suitable manner, respectively, to the heads 31 and 21. Preferably, I provide three spring strips 40 for each of the balls. There may be three or four ribbon springs 40 to each ball and, of course, I am not limited to this construction. The weight of the balls is carried by these 105 springs 40 and each ball has a guide 41 formed with it which extends to and around the stationary hollow standard or post 18 or tubular member, previously referred to. These guides prevent the springs from 110 wabbling when the revolving motion of the balls is suddenly increased or decreased and these guides also act to limit the outward movement of the balls.

The mechanism for shifting and adjusting the head 21 and thus raising or lowering the valve rod 10 comprises a collar 42 which 115 loosely surrounds the upwardly projecting seat or boss 17 and has rotation with relation thereto. The lower end of the extension 22 is peripherally grooved, as at 43, and the collar 42 has an upwardly projecting finger 44 having an inwardly extending tooth which engages in this groove 43. It 120 will thus be seen that any upward movement of the collar 42 will cause an upward movement of the head 21 and that, when the finger 44 which is formed as part of the 125 collar engages with the underside of the 130

gear 28 the gear 28 will also be raised. The collar 42 is diagonally slotted, as at 45, and at the base of this slot is formed a notch 45^a. Projecting radially from the seat 17 is a pin 46 which rides in the slot 45 and which, when the collar is fully raised engages in the notch 45^a. This pin 46 is provided with a roller which rides in the slot 45. A nut 47 larger than the slot engages over the pin. Now, if the collar 42 be rotated in one direction, it will be obvious, that the walls of the slot will ride upon the pin and the collar will be moved upward with relation to the pin and that when the collar is rotated in the opposite direction the collar will be drawn downward. For the purpose of easily rotating this collar and holding it in its rotatably adjusted position, I provide a screw pin 48 or set screw which passes through the collar and which when screwed in, is adapted to engage with the face of the portion 17. This pin may have on it any suitable handle whereby the collar may be rotated by hand, but preferably and as illustrated, I provide a handle 49 which is of considerable length and which has a flexible or universal joint at 50 with the pin 48. The handle is provided at its extremity with a hand wheel 51 whereby it may be rotated. Inasmuch as the joint at 50 is universal or flexible it is possible to extend this handle in almost any direction and yet secure a proper movement of the collar and a proper adjustment of the set screw 48. This makes it extremely convenient for the engineer. By pushing upon this handle 49 in one direction the collar will be rotated to cause its elevation and the consequent elevation of the head 21. This through the action of the spring will cause an elevation of the rod 10 and the consequent increased opening of the regulating valve to which the valve rod sections 9 and 10 are connected. By drawing upon the rod 49 the collar may be reversely turned which will cause the lowering of the head 21 and the consequent lowering of the valve rod sections and the closing of the valve. Thus, any desired speed may be easily secured and inasmuch as the valve rod sections 9 and 10 move together with the heads 21 and 31, it will be obvious, that the governor will operate in the same manner for all speed adjustments. In other words, after the opening of the valve has been regulated the governor will operate to control this valve in the usual manner and hold it in its adjusted position. If the collar 42 be rotated in one direction to its full extent it will not only lift the head 21 and the valve rod, but it will completely disconnect the gear 28 from the gear 8 and will hold the valve in its fully open position. Under these circumstances, of course, the shaft 5 will rotate without in any manner rotating the head 21.

Mounted in the bracket 4 is a shaft 52, one end of which is cranked as at 53 and supported upon this cranked end is an idler pulley 54 which is a belt tightening pulley to the extent that it rests upon the belt 7 70 and is supported thereby. If the belt 7 should break the idler pulley will drop and the shaft 52 be rotated. If the belt breaks it is necessary that steam be immediately shut off and to this end, this shaft 52 is 75 operatively connected to the latch 12 to cause a retraction of the latch and a disengagement of the rod section 9 from the rod section 10 upon a dropping of the idler pulley 54. To this end I mount upon the 80 shaft 52 the small winding drum 55 as shown most clearly in Fig. 3, and attached to this winding drum and to the bent end 13 of the latch 12 is a chain 56. Now when the pulley 54 drops by the breaking of the 85 belt 7 the drum 55 will be turned in the direction of the arrow 53 which will wind up the chain and withdraw the detent tooth 14 from its engagement with the notch 15. Only a very slight movement of the device 90 is required. As soon as this occurs the coupling 11, the shaft 9 and the latching device will drop, shutting off the regulating valve.

In many cases, as for instance where the traction engine is traveling upon a road, it is 95 necessary to provide means for not only disconnecting the governor upon the driving shaft, but for preventing the dropping of the idler 54 when the belt 7 breaks, and thus prevent the steam from being shut-off 100 in case the belt breaks. For this purpose, I provide upon the shaft 52 a hook 57 which is adapted to engage over the pin 48 when the collar 42 is fully raised and resting in the notch 45^a, that is when the parts are in 105 the position shown in Fig. 2.

The operation of my invention will be obvious by what has gone before. Under normal circumstances the shaft 5 is driven by means of the belt 7 and motion is communicated to the head 21 through the gears 8 and 28, and this in turn causes rotation of the balls 39 and of the head 31. If it is desired to increase the speed of the engine without changing the belt 7, the collar 42 is shifted 110 to any extent required. This will raise the valve rod sufficiently to open the regulating valve to a degree commensurate with the desired speed of the engine. If the speed of the engine increases beyond this point, the 115 governor balls will fly outward and the valve rod will move downward against the force of the spring 23. The spring 29 under these circumstances will keep the gears 8 and 28 constantly meshed. If it is desired 120 to entirely disconnect the governor from the shaft 5 and hold the throttle valve wide open the sleeve 42 is turned sufficiently around to cause it to be lifted to its extreme upward position upon the pin 46 and under 125 130

these circumstances the gears 28 and 8 will be entirely disconnected. When the sleeve 42 is lifted to its extreme upward position and the pin 46 rests within the notch 45^a, then the hook 57 will engage with the pin 48 if the belt 7 breaks. If the belt tightening pulley is used and the belt breaks, it is obvious that, immediately the lower section of the valve rod will be released from its engagement with the upper section and the valve rod will drop, thus closing the governor valve and stopping the engine.

The advantages of my invention are as follows: The governor can almost instantly be adjusted for any desired speed or by shifting the collar 42 still farther around the seat 17, the governor may be thrown out of service, which thus takes all unnecessary wear and strain off the governor. This is particularly necessary when traveling on the road. When the governor is thrown out of service it is obvious that a full boiler pressure is at the engineer's hand. This is particularly convenient in traction engines as it not only takes steam from the governor but it permits the engine to run at a good speed. In the ordinary traction engine it is necessary to remove the belt 7 in order to disconnect the governor and this is a considerable trouble and this necessity of continually taking off and putting on the belt in order to get the desired speed out of the engine for all kinds of work is one of the great nuisances incident to traction engines as ordinarily constructed. With the ordinary governor, if the traction engine is running upon a road with the belt left on, sufficient speed cannot be secured to make good time on the road. Further than this, there will be constant danger of accident because, if, when on a hill, the belt 7 should break, it would allow the regulating valve to drop and close and it would practically be impossible to hold the traction engine under these circumstances.

In case the belt should break with my improved governor while on the road, the hook 57 would catch upon the pin 48 and would hold the pulley from dropping down and thus will prevent the steam from being shut off in case the belt breaks. By providing the rod 49 and universal joint 50 the collar 42 may be shifted from almost any direction. This is particularly necessary for traction engines, but is not necessary for stationary engines, as in this case a small handle may be used in place of the relatively long handle connected by the universal joint 48.

It will be seen that any desired belt pulley 6 may be used in connection with this governor without in any way affecting the operation of the governor itself. It will also be seen that I have very much simplified the governor ordinarily used, such as the Pickering governor. The governor can be ad-

justed to any desired speed of the engine while the engine is in motion and can be thrown in and out of gear while the engine is running without injury to the engine or to the governor. When the engine is running if the bevel gear wheels are thrown into mesh the teeth will not strip because the balls and springs will fly outward and this relieves the gears of any sudden jerk.

With my governor, as before stated, it is not necessary to remove the governor belt every time the engine is to be changed from stationary work to road traveling. It is usually necessary to so remove the governor belt because the speed of the engine, when it is stationary and used for operating machinery is not sufficient to let the engine travel fast enough to make proper time on a good road. Under these circumstances it is customary to remove the belt and thus leave the governor idle. This is entirely obviated by my improvement which will prevent disconnection between the governor and its driving means and thus permits a full boiler pressure being used to road running.

It is reiterated that, when the collar 42 is lowered and the gears 28 and 8 are in mesh, then, if the belt 17 breaks, the hook 57 cannot engage with the pin 48. It is only when the gears 28 and 8 are out of mesh, as in Fig. 2, and the belt breaks that the hook 57 will engage the pin 48, in the manner shown in Fig. 5. This will prevent the cutting off of the steam.

The belt tightening and the means for automatically closing the steam valve upon breakage of the belt are reversible so that, when it is necessary to run the belt in the opposite direction, the lugs upon which the shaft 52 is pivotally supported are cast upon opposite sides of the bracket 4 so that the latching arrangement and winding drum could be placed on the other side of the bracket.

While I have illustrated what I believe to be the best form of my invention, I do not wish to be limited thereto as it is obvious that any changes might be made in the details thereof without departing in any way from the spirit of the invention.

Having thus described my invention, what I claim and desire to secure by Letters Patent is:—

1. A governor of the character described including a driving gear, a driven gear, governor weights operatively connected to the driven gear, a valve rod controlled by said governor weights and means for shifting the gears relative to each other to thereby connect or disconnect said gears.

2. A governor of the character described including a driving shaft, a gear wheel mounted thereon, a driven gear wheel, governor weights operatively connected to the driven gear wheel to rotate therewith, a

valve rod operatively connected to and controlled by the governor weights, and means for shifting the gear wheels into or out of engagement with each other.

5. 3. A governor of the character described including a driving shaft, a beveled gear wheel mounted thereon, a driven beveled gear wheel, a rotatable element to which the driven beveled gear wheel is connected, governor weights operatively connected to said element, a valve rod operatively connected to and controlled by said governor weights, and means for shifting said element to carry the gear wheel coacting therewith into or

15 out of mesh with the driving gear wheel.

4. A governor of the character described including a driving shaft, a beveled gear wheel mounted thereon, a driven beveled gear wheel, a rotatable element operatively connected to the driven gear wheel to rotate therewith, governor weights connected to the rotatable element, a valve rod operatively connected to the governor weights and controlled thereby, resilient means for urging the rotatable element toward the driving beveled gear wheel, and means for shifting the rotatable element against the force of the resilient means to thereby carry the driven gear wheel out of mesh with the driving gear wheel.

5. In a governor of the character described, a valve, a valve-rod, upper and lower rotatable elements, the upper rotatable element controlling the movements of the valve-rod, governor mechanism connecting the upper and lower rotatable elements and controlling the movements of the upper rotatable member, a rotary element splined to the lower rotatable element and having a limited longitudinal movement thereon, and means for moving the lower rotatable element within certain limits independently of the rotary element for adjustment of the valve, or to move both the lower rotatable and the rotary elements together to throw the governor mechanism out of action.

6. In a governor of the character specified, a valve rod held against rotation but free to move longitudinally, a rotary and longitudinally movable element mounted coaxially with the valve rod, governor weights operatively connected with the valve rod and with the rotary and longitudinally movable element, a rotary driving element splined to the rotary and longitudinally movable element, a controllable rotary element connected to the rotary and longitudinally movable element to move therewith but admit of each element having an independent rotary movement imparted thereto, a support for the controllable rotary element, and co-acting means between the support and the controllable rotary element to impart a longitudinal movement to the controllable rotary element when rotated to effect an adjust-

ment of the valve independent of its automatic adjustment by means of the governor weights.

7. In a governor of the character specified, a valve rod held against rotation but free to move longitudinally, a rotary and longitudinally movable element mounted co-axially with the valve-rod, governor weights operatively connected with the valve rod and with the rotary and longitudinally movable element, a rotary driving element splined to the rotary and longitudinally movable element and having a limited longitudinal movement with reference thereto, an operating element for the rotary driving element, yielding means between the rotary and longitudinally movable element and the driving element to hold the latter in contact with the operating element during a part of the longitudinal movement of the rotary and longitudinally movable element, a controllable rotary element connected to the rotary and longitudinally movable element to move therewith but admit of each element having an independent rotary movement imparted thereto, a support for the controllable rotary element, and co-acting means between the support and the rotary element to impart a longitudinal movement to the rotary element when rotated to effect an adjustment of the valve independent of its automatic adjustment by means of the governor weights.

8. In a governor of the character described, a driving shaft, a beveled gear wheel mounted thereon, a valve rod extended at right angles to the driving shaft, a controlling valve connected thereto, a rotatable element surrounding the valve rod, a beveled gear wheel carried thereby and engaging the driving beveled gear wheel, a spring bearing at one end against an operative portion of the valve rod and at its other end bearing against the last named rotatable element, the second rotatable element surrounding the valve rod, governor balls, operative connections between the governor balls and the said rotatable elements to cause a movement of the second named rotatable element toward the first named element upon an outward movement of the governor balls, an operative connection between the second named rotatable element and the valve rod, and means for shifting the first named rotatable element and the valve rod, whereby to secure an adjustment of the valve independently of the control of said valve by the governor balls.

9. In a governor of the character described, a regulating valve, a valve rod connected thereto, a lower rotatable element loosely surrounding the valve rod, a beveled gear wheel slidably mounted on but rotatable with the said element, a driving shaft extending at right angles to the valve rod, a beveled gear wheel mounted thereon mesh-

6
ing with the first named beveled gear wheel, an upper rotatable element loosely surrounding the valve rod, springs extending between and operatively connected to the upper and lower rotatable elements, governor balls carried by said springs, a cap carried by the upper rotatable element and rotatably engaging the upper end of the valve rod, a coil spring surrounding the valve rod, bearing at its lower end upon the upper face of the lower rotatable element and at its upper end having operative engagement with the valve rod, and means for raising or lowering the lower rotatable element independently of the beveled gear carried thereby, to thereby raise or lower the valve rod, the upper and lower rotatable elements, and the governor balls.

10. In a governor of the character described, a regulating valve, a valve rod connected thereto, a lower rotatable element loosely surrounding the valve rod, a beveled gear wheel slidably mounted on but rotatable with the said element, a driving shaft extending at right angles to the valve rod, a beveled gear wheel mounted thereon meshing with the first named beveled gear wheel, an upper rotatable element loosely surrounding the valve rod, springs extending between and operatively connected to the upper and lower rotatable elements, governor balls carried by said springs, a cap carried by the upper rotatable element and rotatably engaging the upper end of the valve rod, a coil spring surrounding the valve rod, bearing at its lower end upon the upper face of the lower rotatable element and at its upper end having operative engagement with the valve rod, a spring disposed between the lower rotatable element and said beveled gear wheel, and means for raising or lowering the lower rotatable element independently of the beveled gear carried thereby, to thereby raise or lower the valve rod, the upper and lower rotatable elements, and the governor balls.

11. In a governor of the character described, a regulating valve, a valve rod connected thereto, a lower rotatable element loosely surrounding the valve rod, a beveled gear wheel slidably mounted on but rotatable with the said element, a driving shaft extending at right angles to the valve rod, a beveled gear wheel mounted thereon meshing with the first named beveled gear wheel, an upper rotatable element loosely surrounding the valve rod, springs extending between and operatively connected to the upper and lower rotatable elements, governor balls carried by said springs, a cap carried by the upper rotatable element and rotatably engaging the upper end of the valve rod, a coil spring surrounding the valve rod, bearing at its lower end upon the upper face of the lower rotatable ele-

ment and at its upper end having operative engagement with the valve rod, a spring disposed between the lower rotatable element and said beveled gear wheel, means for raising or lowering the lower rotatable element independently of the beveled gear carried thereby, to thereby raise or lower the valve rod, the upper and lower rotatable elements, and the governor balls, and means for holding the rotatable element in its adjustable position.

12. In a mechanism of the character described, a driving shaft, a beveled gear wheel mounted thereon, a rotatable element having an axis disposed at right angles to the driving shaft, a spring urging the rotatable element toward the driving shaft, a beveled gear wheel splined upon the rotatable element and normally engaging with the driving beveled gear wheel, yielding means urging the driven beveled gear wheel into engagement with the driving beveled gear wheel, a collar bearing against one end of the rotatable element opposite the spring and rotatable around the axis thereof, a cam face formed upon the collar, a fixed member with which the cam face engages to cause a shifting of the collar against the spring or against the rotatable element upon a rotation of the collar, and means for causing a rotation of the collar to a predetermined extent and for holding the collar in its rotatively adjusted position.

13. In a governor of the character described, a regulating valve, a valve rod formed in upper and lower sections, the lower section being connected with the valve, centrifugally actuated controlling mechanism connected to the upper section, an idler adapted to rest upon a band and be supported thereby in a raised position, means normally connecting the two sections of the valve rod to each other, means actuated by a fall of said idler for disconnecting said sections, said means including a latch normally connecting the two sections, a barrel operatively connected to the arm to rotate in one direction upon the fall of the arm, and a flexible connection from said barrel to said latch to cause a withdrawal of the latch upon a fall of the arm.

14. In a mechanism of the character described, a driving shaft, a pulley carried thereby, a regulating valve, a valve rod extending at right angles to the driving shaft, said rod being formed in two sections, the lowermost section being connected to the regulating valve, centrifugally actuated controlling mechanism connected to the upper section of the rod, means on the driving shaft for rotating said centrifugally actuated mechanism, a shaft extending parallel to the driving shaft and having a cranked arm at one end, a pulley supported thereby and adapted to rest upon a

belt passing from the first named pulley, a coupling inclosing the joint between the upper and lower sections of the rod, a longitudinally movable latching member passing through said coupling and having a tooth engaging with the upper section of the rod, a spring held said latch member in such engagement, a barrel mounted upon the second named shaft, a flexible connection

from said barrel to the latch member, and 10 means movable into position to prevent the dropping of said idler pulley.

In testimony whereof I affix my signature in presence of two witnesses.
